3 Sheets-Sheet 1

This technical drawing illustrates a complex mechanical assembly, possibly a reel or spool mechanism. The drawing is a line drawing with various components labeled with numbers. Key labeled parts include:

- 17, 23, 30: Components on the left side, possibly related to a wheel or drum.
- 24: A rectangular frame or housing.
- 22: A component located within the rectangular frame.
- 9: A small circular component.
- 24: A rectangular frame or housing.
- 25: A component located within the rectangular frame.
- 26: A component located within the rectangular frame.
- 27: A circular component.
- 13, 28: Components on the left side, possibly related to a wheel or drum.
- 29: A component located within the rectangular frame.
- 31, 32, 33, 34, 35, 36, 37, 38, 39, 40, 41, 42, 43, 44, 45, 46, 47, 48, 49, 50, 51, 52, 53, 54: Various components distributed across the assembly, including gears, shafts, and structural elements.
- 1: A component on the right side.

UNITED STATES PATENT OFFICE.

WILLIAM E. COOK, OF ST. GEORGE, NEW YORK, ASSIGNOR TO PEERLESS INSULATED WIRE AND CABLE COMPANY, OF NEW YORK, N. Y., A CORPORATION OF DELAWARE.

WIRE-COVERING MACHINE.

Application filed November 29, 1921. Serial No. 518,576.

To all whom it may concern:

Be it known that I, WILLIAM E. COOK, a subject of the King of the United Kingdom of Great Britain and Ireland, residing at St. 5 George, in the borough of Richmond, city of New York, county of Richmond and State of New York, have invented certain new and useful Improvements in Wire-Covering Machines, of which the following is a specification, reference being had therein to the accompanying drawings, which form a part thereof.

My invention relates to wire covering machines, and more particularly to improvements in the type of machine for applying an insulating body consisting of a strip of cotton sliver, spirally about a conducting wire while the wire is moving longitudinally thereof through the machine.

20 Machines of the general type to which my invention relates are in extensive use at the present time, the present invention relating more particularly to an arrangement and construction of parts which will permit the 25 operation of the machine at much higher speeds than has heretofore been possible, while ensuring a compactness of structure which will facilitate the mounting and removal of cans containing the sliver, and permit ready access to the compacting head.

In a machine embodying my invention, the power is applied directly to the spindle of the compacting and winding head, which spindle is mounted in a stay frame extending transversely of the machine, in which frame the shaft of the main power pulley is also journaled. This construction is utilized as affording long bearings for said spindle, and permitting the utilization of the lower 40 end of the spindle as a means of suspension for a light rigid metal carrier for the containers, thus so materially reducing the weight of the moving parts of the machine as to minimize the moving inertia of parts to 45 an extent to facilitate the operation of the machine at high speed while permitting a rapid stoppage of the machine in the event of the necessity for such action.

In machines of the type to which my invention relates, the wire is drawn through the machine at a uniform speed through the medium of a sheave about which the wire passes, a characteristic of the invention being a simple and rigid mechanism by which

said sheave will be actuated in synchronism 55 with the covering mechanism so as to ensure substantial uniformity in the condition of the covering sliver throughout the entire length of the wire.

The machine of my invention embodies 60 therein a band brake structure acting upon a drum carried directly by the spindle for the compacting and winding head, which drum also acts as a support for the container-carrying frame, a construction which 65 not only ensures simultaneous stoppage of the compacting and winding head and said carrying frame, but prevents the racking of the machine as a result of such stoppage, however infrequent.

70 The carrying frame itself is so constructed as to support the containers for the sliver with their axes disposed horizontally, which construction causes centrifugal action to hold the coils of sliver in position within 75 the container and thus minimize likelihood of the entanglement thereof while the machine is in operation, and ensures the proper feeding movement of the strip so as to place no limitation upon the speed of the 80 machine because of the tendency of the sliver to become entangled. This characteristic of the machine is not broadly new to the machine of my present application, the 85 novelty in which resides more particularly in that construction of the container-carrying frame which will permit the containers to be quickly mounted in and removed from said frame while ensuring against their displacement while the machine is in operation.

90 The invention consists primarily in a wire covering machine embodying therein a cross frame intermediate the top and bottom of the machine having vertical bearings 95 therein, a hollow spindle mounted in said bearings, a compacting head surmounting said spindle and including a die, the opening of which is in axial alinement with said spindle, a main power shaft also mounted in bearings in said cross frame, geared connection between said power shaft and said spindle, means adapted to impart continuous traverse to a wire passing through said hollow spindle, and a container carrier suspended from and rotatable with said spindle, consisting of a plurality of horizontally 100 extending saddles adapted to receive a bar-

100

105

rel container and engage the outer end thereof; and in such other novel features of construction and combination of parts as are hereinafter set forth and described, and 5 more particularly pointed out in the claims hereto appended.

Referring to the drawings,

Fig. 1 is a side view of a machine embodying my invention;

10 Fig. 2 is a vertical section on the line 2—2 of Fig. 1 upon a larger scale;

Fig. 3 is a detail plan view of the counter shaft mechanism for transmitting power from the main power shaft to the wire 15 feeding and rewind mechanism;

Fig. 4 is a detail plan view of the brake mechanism; and

20 Fig. 5 is a plan view of the container-carrying frame with its uprights shown in sections.

Like numerals refer to like parts throughout the several views.

In the embodiment of my invention shown in the drawings, the base of the machine is 25 shown at 1 and the side frames at 2 and 3. Extending between and rigidly secured to said side frames is a cross frame 4 having therein vertical bearings 5 and 6 for the hollow spindle 7 which supports the compacting and winding head 8. This winding head includes therein a compacting die 9, the detailed construction of which is immaterial to the present invention and will therefore not be described in detail. In the 30 cross frame 4 are horizontal bearings 10 and 11 for the main power shaft 12.

The shaft 12 carries a pulley 13 through which power is applied thereto and is 40 geared with the spindle 7 by means of the intermeshing bevelled gears 14 and 15 carried by said shaft and said spindle respectively.

The gear 15 in addition to serving as a power applying means to the spindle 7 also 45 serves as a thrust bearing for said spindle.

Mounted in bearings on the side frames 2 and 3 above the cross frame 4 is a shaft 16 carrying a sheave 17 about which the covered wire is wound before passing to the 50 rewind mechanism, which sheave is actuated in a manner to impart uniform lineal traverse to the wire at a desired speed to secure the proper spiral winding of the sliver upon the wire.

55 This sheave 17 is idly mounted upon the shaft 16 but is adapted to be connected thereto by a clutch mechanism 18.

The sheave 17 and the rewind mechanism including the traverse mechanism are all 60 driven from the shaft 12 through a mechanism which will now be described.

The cross frame 4 upon the side thereof adjacent the side frame 3, has alined bearings 19—20 therein, which are in axial alinement with the bearings 10 and 11 and have

mounted therein a shaft 21. Said shaft 21 is connected with the shaft 16 by means of the sprocket wheels 22 and 23 and the co-operating sprocket chain 24, the wheel 23 being of greater diameter than the wheel 22, thus giving a speed reduction to the shaft 16 through this chain and sprocket mechanism.

The shaft 21 is driven from the shaft 12 by means of the gears 25 and 26 and the speed reducing mechanism 26^a carried by the counter shaft 27, which gears respectively are meshed with the gear 28 carried by the shaft 12 and the gear 29 carried by the shaft 21. The gear 25 is of relatively larger diameter than the gear 28, the gears 26 and 29 being of the same diameter.

In this manner a direct rigid drive from the power shaft 12 to the intermediate shaft 21 is secured with a material reduction of speed in the shafts 21 and 16 so as to cause the sheave 17 to have the desired R. P. M. relative to the R. P. M. of the spindle 7 and the container-carrying frame for applying the covering sliver to the wire.

The lower end of the spindle 7 projects below the cross frame 4 and has secured thereto so as to be rotatable therewith, a circular plate 30, the edge of which serves as a brake drum, and which is provided with bosses adapted to receive and retain the uprights 31 of the container-carrying frame, which is preferably made of metal tubing so as to have this frame as light as possible while imparting thereto sufficient rigidity to ensure the maintenance of the proper position of each container with relation to the wire being covered.

The uprights 31 of said container-carrying frame are four in number rectangularly arranged and provided with horizontally extending stay tubes 32.

Connected to the lower ends of said uprights 31 is an annular plate 33 secured to which are two pairs 34 and 35 of saddle-forming tubes rectangularly arranged with relation to each other and having their ends connected by the rods 36 and 37 respectively.

The portions of the annulus 33 intermediate the tubes 34 and 35 respectively at diametrically opposite points, is segmentally formed and depressed as shown at 38 so that each barrel container 39 adjacent the open top thereof will seat upon a segmental or arcuate depressed portion. The portions of the tubes of each pair 34 and 35 within said annulus 33 are curved or formed downwardly as at 40—41 so as to bring this portion at or below the plane occupied by the lowermost diameter of the several containers 39 while increasing the rigidity of the saddle structure.

Adjacent the rear of the machine is a shaft 42 upon which a rewind reel 43 is adapted to be idly mounted, this reel being adapted

to be connected with the shaft 42 by means of a crank 44 carrying a screw-threaded or other stud 45 adapted to enter a recess in one of the end plates of the reel 43, said 5 crank 44 being secured by means of a set screw 46, or in any other desired manner, to said shaft 42 so as to rotate therewith.

Mounted in the side frame 3 adjacent and parallel with the shaft 42 is a shaft 47 carrying a small pulley 48 connected by means of the belt 49 with a large pulley 50 carried by the shaft 16. By the employment of a belt and pulley connection between the shafts 16 and 47, slippage of said belt is permitted 10 to compensate for the gradual increase in diameter of the wire as it is wound upon the reel 43.

Carried by the shafts 42 and 47 respectively are the intermeshing gears 51 and 52 20 so as to ensure simultaneous rotation of the sheave 17 and reel 43 at a fixed speed ratio.

The shaft 47 is connected by means of the chain and sprocket mechanism 53 with the transverse mechanism 54 which mechanism 25 being old and well known in this art, requires no detailed description, its function being merely to impart a lateral feed to the wire as it is passing from the sheave 17 to the reel 43 in a manner to cause it to wind 30 properly upon the latter.

Carried by the frame 4 are brackets 55 which support a band brake 56, the band of which brake is connected with studs 57 acted upon by springs 58 as shown to normally 35 hold said brake band out of engagement with the drum 30.

One end of the brake band is secured to a fixed stud 59 and the other end thereof is secured to the shorter arm 60 of the hand 40 lever 61 pivoted at 62 to the frame 4.

The spacing of the tubes 34 and 35 of each pair apart as shown has the two-fold effect of permitting the barrel containers to be quickly mounted in the supporting frame 45 therefor and causing said containers to be held against displacement either from centrifugal force or atmospheric resistance, the bottom of said containers engaging the connecting end bars 36-37 while the portion 50 thereof adjacent the open top will engage the stay tubes 32.

Adjacent the bottom of the machine is a guide pulley 63 about which the conductor 55 wire 64 passes to the covering mechanism, one periphery of said pulley being in axial alignment with the opening in the spindle 7.

In Fig. 2 I have shown the end of one strip of sliver A drawn from the barrel container for same and affixed to the wire as 60 when starting a run of the machine.

The operation of the herein described mechanism is substantially as follows:—

In starting a run of the machine, the wire 65 is brought from any desired source, passed about the pulley 63 and connected with a

rope or other strand which is threaded through the die 9 and spindle 7, and passed about the sheave 17. The clutch 18 of said sheave is used to disconnect it from the shaft 16 so as to permit the use of this 70 sheave in drawing the end of the wire toward the spindle to a point where the ends of the sliver strips may be applied thereto. Ordinarily this wire is coated with an adhesive so as to ensure a permanent bond between the innermost ply of sliver of the wire.

After the ends of the sliver strips have been properly applied to the wire, the clutch 18 is set and power is applied to the machine through the shaft 12 and pulley 13. The rotation of said shaft 12 will, through the gears 14 and 15, rotate the spindle 7, the compacting and winding head 8 and the die 9 thereof, and the container supporting frame, and will at the same time rotate the shaft 21 through the gears 25 and 26 and the counter shaft 27 so as to cause the chain and sprocket mechanism 22-23-24 to 80 rotate the shaft 16 and sheave 17, thus imparting lineal traverse to the wire through the medium of said sheave which gives the desired pitch to the sliver strips as a result of the rotation of the barrels 39.

So long as the shaft 16 is rotated, the pulley 50 will rotate the shaft 47 through the belt 49 and pulley 48, thus simultaneously imparting rotary movement to the reel 43 and lateral movement to the traverse 90 mechanism 54 through the chain and sprocket mechanism 53.

Extreme accuracy in the actuation of the rewind reel and of the traverse mechanism is unnecessary, slippage of the belt 49 occurring whenever the sheave 17 does not supply sufficient slack wire to permit the 100 reel 43 to turn freely.

Binding strands are applied to the compacting sliver upon the wire by means of the compacting and winding head 8 and 9. The arrangement of the shafts 12 and 21 and the geared connection between said shaft as well as the geared connection between the shaft 12 and the spindle 7, will ensure positive actuation of these mechanisms with a uniform movement avoiding any of such sudden stops and starts as would tend to attenuate or break the sliver, and ensuring a smooth uniform application of the sliver strips to the wire with the operation of the machine at a speed many fold greater than has heretofore been the practice, and without likelihood of a development of conditions within the machine which will result in breakage of the sliver.

While the container-supporting frame is very light in weight, the structure employed gives great rigidity thereto and the mounting and removal of the barrel containers is greatly facilitated.

While the machine is operated at the highest speed, moving inertia developed in the container-supporting frame has not been found sufficiently great to interfere with the 5 braking action upon the driving mechanism, nor to cause distortion of the frame as a result of sudden stoppage or starting of the machine.

The use of the annulus 33 will hold the 10 tubes 34 and 35 of each pair absolutely rigid adjacent the point of application of the sliver to the wire, so that even should the outer ends of these tubes yield slightly, this will not in any way effect the relation of the 15 open top of the barrels to the wire.

The stay rods 32 will prevent disarrangement of the uprights 31 and also co-operate with the saddle formed by the tubes 34 and 20 35 in holding the barrels against vertical displacement from vibrations or other causes. The end rods 36-37 will check any 25 tendency of an outward movement of the barrel containers as a result of centrifugal force due to the development of high speeds in the machine.

In mounting and removing the barrels from the machine, it is merely necessary to place the open top thereof beneath a cross-bar 32 by tilting the container, and drop the 30 barrel between the pair of spaced tubes 34 or 35 and either bring the bottom thereof into engagement with a rod 36 or 37, or permit the barrel to adjust itself to this position while the machine is in operation.

35 It is of great importance with a high speed machine, that the axis of the barrel should be horizontally arranged, since under this condition the coils of sliver within the barrel as they are formed in delivering this 40 sliver to the barrels from the carding machine, will not be disturbed by any conditions developed during a run of the machine at the higher speeds, thus permitting a free uncoiling of the sliver strip and a free running thereof from the container to the wire.

45 Heretofore in machines for applying sliver strips to wires, utilizing barrel containers, the entanglement of the strip within the barrel has been a source of serious difficulties resulting in a material loss in the capacity of the machine, due to the tendency of the coiled sliver to pack as a result of the action of centrifugal force, since at the best this sliver while in the container is in a 50 fluffy mass, which may be readily compacted and will thus have a tendency to move outwardly of the axis of rotation of the barrel. The sliver if delivered from the carding machine is coiled in a series of overlapping 55 coils or convolutions and not about a single axis, so that any compaction of the mass radially of the barrel will frequently result in the entanglement of different coils.

It is therefore apparent that if the pressures are axially of the barrel, there will be

no tendency to close the coils or convolutions one upon the other, so that as the sliver is withdrawn it will uncoil freely.

It is apparent that the curved depressed portions 40 and 41 of the tubes 34 and 35 70 of each pair will give great rigidity to the container-supporting frame.

Having described the invention, what I claim as new and desire to have protected by Letters Patent, is:—

75 1. A wire covering machine embodying therein a cross frame intermediate the top and bottom of the machine having vertical bearings therein, a hollow spindle mounted in said bearings, a compacting head surrounding said spindle and including a die, the opening of which is in axial alignment with said spindle, a main power shaft also mounted in bearings in said cross frame, geared connection between said power shaft 80 and said spindle, means adapted to impart continuous traverse to a wire passing through said hollow spindle, and a container carrier suspended from and rotatable with said spindle, consisting of a plurality of 85 horizontally extending saddles adapted to receive a barrel container and engage the outer end thereof.

90 2. A wire covering machine embodying therein a cross frame intermediate the top and bottom of the machine having vertical bearings therein, a hollow spindle mounted in said bearings, a compacting head surrounding said spindle and including a die, the opening of which is in axial alignment 95 with said spindle, a main power shaft also mounted in bearings in said cross frame, geared connection between said power shaft and said spindle, a sheave about which a wire passing through said hollow spindle 100 passes, means imparting uniform angular speed to said sheave, consisting of a shaft mounted in said cross frame, speed reducing connections between said shaft and said sheave, and speed reducing gearing connecting said main power shaft with said last named shaft, and a container carrier suspended from and rotatable with said spindle, consisting of a plurality of 105 horizontally extending saddles adapted to receive a barrel container and engage the outer end thereof.

110 3. A wire covering machine embodying therein a cross frame intermediate the top and bottom of the machine having vertical bearings therein, a hollow spindle mounted in said bearings, a compacting head surrounding said spindle and including a die, the opening of which is in axial alignment 115 with said spindle, a main power shaft also mounted in bearings in said cross frame, geared connection between said power shaft and said spindle, a sheave about which a wire passing through said hollow spindle 120 passes, means imparting uniform angular 125 speed to said sheave, consisting of a shaft mounted in said cross frame, speed reducing connections between said shaft and said sheave, and speed reducing gearing connecting said main power shaft with said last named shaft, and a container carrier suspended from and rotatable with said spindle, consisting of a plurality of horizontally extending saddles adapted to receive a barrel container and engage the outer end thereof.

130

speed to said sheave, consisting of a shaft mounted in said cross frame, speed reducing connections between said shaft and said sheave, gear wheels upon said main power shaft and said last named shaft respectively, the gear upon said main power shaft being of relatively smaller diameter than said other gear, a counter shaft, and gears thereon meshing respectively with the gears upon 10 said main power shaft and said other shaft, whereby the R. P. M. of said sheave will be very much lower than the R. P. M. of said spindle, and a container carrier suspended from and rotatable with said spindle, consisting of a plurality of horizontally extending saddles adapted to receive a barrel container and engage the outer ends thereof.

4. A wire covering machine embodying 20 therein a cross frame intermediate the top and bottom of the machine having vertical bearings therein, a hollow spindle mounted in said bearings, a compacting head surmounting said spindle and including a die, 25 the opening of which is in axial alinement with said spindle, a main power shaft also mounted in bearings in said cross frame, geared connection between said power shaft and said spindle, means adapted to impart 30 continuous traverse to a wire passing through said hollow spindle, a circular plate secured to said spindle below said cross frame, a plurality of pairs of uprights pendant from said frame, and horizontally extending 35 saddles adapted to receive barrel containers for the sliver and engage the outer ends thereof.

5. A wire covering machine embodying 40 therein a cross frame intermediate the top and bottom of the machine having vertical bearings therein, a hollow spindle mounted in said bearings, a compacting head surmounting said spindle and including a die, the opening of which is in axial alinement 45 with said spindle, a main power shaft also mounted in bearings in said cross frame, geared connection between said power shaft and said spindle, means adapted to impart continuous traverse to a wire passing 50 through said hollow spindle, and a container carrier suspended from and rotatable with said spindle, consisting of an annular plate, two pairs of horizontally extending saddle-forming members, the portion of said annulus intermediate the tubes of each pair being segmentally formed and depressed, and the portions of the tube of each pair within said annulus being curved and formed downwardly to a point below the plane of said annulus, the members of one pair extending at right angles to the members of the other pair and being spaced apart to receive therebetween the curved face of a barrel container, and a plate 55 connecting the opposite ends of each pair of members, whereby outward movement of the container, while the machine is in operation, is restrained, cross braces connected with said uprights and distant from said members so as to be adapted to engage the side of a barrel container therein.

6. A wire covering machine embodying movement of the container, while the machine is in operation, is restrained.

70 therein a cross frame intermediate the top and bottom of the machine having vertical bearings therein, a hollow spindle mounted in said bearings, a compacting head surmounting said spindle and including a die, the opening of which is in axial alinement with said spindle, a main power shaft also 75 mounted in bearings in said cross frame, geared connection between said power shaft and said spindle, means adapted to impart continuous traverse to a wire passing through said hollow spindle, a circular plate 80 secured to said spindle below said cross frame, a plurality of pairs of uprights pendant from said frame, an annular plate carried by said uprights, two pairs of horizontally extending saddle-forming members, the 85 portion of said annulus intermediate the tubes of each pair being segmentally formed and depressed, and the portions of the tube of each pair within said annulus being curved and formed downwardly to a point 90 below the plane of said annulus, the members of one pair extending at right angles to the members of the other pair and being spaced apart to receive therebetween the curved face of a barrel container, and a plate 95 connecting the opposite ends of each pair of members, whereby outward movement of the container, while the machine is in operation, is restrained, cross braces connected with said uprights and distant from 100 said members so as to be adapted to engage the side of a barrel container therein.

7. A wire covering machine embodying 105 therein a cross frame intermediate the top and bottom of the machine having vertical bearings therein, a hollow spindle mounted in said bearings, a compacting head surmounting said spindle and including a die, the opening of which is in axial alinement with said spindle, a main power shaft also 110 mounted in bearings in said cross frame, geared connection between said power shaft and said spindle, means adapted to impart continuous traverse to a wire passing through said hollow spindle, a circular plate 115 secured to said spindle below said cross frame, a plurality of pairs of uprights pendant from said frame, horizontally extending saddles adapted to receive barrel containers for the sliver and engage the outer 120 ends thereof, a band brake operative upon the edge of said circular plate, and supports for the band of said brake carried by said cross frame.

8. A wire covering machine embodying 125 therein a cross frame intermediate the top and bottom of the machine having vertical bearings therein, a hollow spindle mounted in said bearings, a compacting head surmounting said spindle and including a die, 130

the opening of which is in axial alinement with said spindle, a main power shaft also mounted in bearings in said cross frame, geared connection between said power shaft and said spindle, means adapted to impart continuous traverse to a wire passing through said hollow spindle, a circular plate secured to said spindle below said cross frame, a plurality of pairs of uprights pendant from said frame, horizontally extending saddles adapted to receive barrel containers for the sliver and engage the outer ends thereof, a band brake operative upon the edge of said circular plate, supports for the band of said brake carried by said cross frame, studs carried by said band brake and extending through said supports, and springs acting between said studs and said supports for normally holding said band brake out of engagement with said plate.

9. A wire covering machine embodying therein a cross frame intermediate the top and bottom of the machine having vertical and hollow spindle mounted with said spindle, a main power shaft also mounted in bearings in said cross frame, and said spindle, a sheave about which a wire passing through said hollow spindle passes, means imparting uniform angular speed to said sheave, consisting of a shaft mounted in said cross frame, speed reducing connections between said shaft and said sheave, gear wheels upon said main power shaft and said last named shaft respectively, the gear upon said main power shaft being of relatively smaller diameter than said other gear, a counter shaft, and gears thereon meshing respectively with the gears upon said main power shaft and said other shaft, whereby the R. P. M. of said sheave will be very much lower than the R. P. M. of said spindle, a circular plate secured to said spindle below said cross frame, a plurality of pairs of uprights pendant from said frame, horizontally extending saddles adapted to receive barrel containers for the sliver and engage the outer ends thereof, a band brake operative upon the plate supports for the

25 bearings in said bearings, a compacting ball in said spindle and including a die, axial alinement edge of said brake carried by said frame, studs carried by said band brake and supports, and springs

carried by said cross frame, studs carried by said band brake and extending through said supports, springs acting between said studs and said supports for normally holding said band brake out of engagement with said plate, a rewind mechanism below said sheave, a traverse mechanism intermediate said sheave and said rewind mechanism, and means whereby said traverse mechanism and 10 said rewind mechanism are actuated from

the same source of power and at relatively higher speed than said sheave.

In witness whereof I have hereunto affixed my signature, in the presence of two subscribing witnesses, this 22nd day of November, 1921.

WILLIAM E. COOK.
